LOUIS G. LIPPMAN, OF YONKERS, NEW YORK, AND FREDERICK E. DIXON, OF SCOTCH PLAINS, NEW JERSEY.

WATER HEATER.

1,405,789.

Specification of Letters Patent. Patented Feb. 7, 1922.

Application filed June 5, 1920. Serial No. 386,915.

To all whom it may concern:

Be it known that we, LOUIS G. LIPPMAN and FREDERICK E. DIXON, citizens of the United States, and residents, respectively, 5 of the city of Yonkers, county of Westchester, and State of New York, and town of Scotch Plains, county of Union, State of New Jersey, have invented certain new and useful Improvements in Water Heaters, of 10 which the following is a specification.

This invention relates to water heaters and has for its object the construction of a stove grate, generally spiral in outline, such spirals being hollowed to form pipes in 15 a hot water system.

Fig. 1 is a plan view partly in section of such grate and Fig. 2 is a cross section on line 2—2 of Fig. 1.

In the figures, 1 is the grate consisting 20 of a special hollow pipe system 2 terminating near its center in a threaded-connection 3 communicating with an inlet pipe 4 designed to lead the cold water from a tank above the apparatus. The pipe system 25 of the grate terminates in a threaded-connection 5 and outlet pipe 6 designed to lead the heated water to the tank. The pipes constituting the grate have preferably 30 a series of spider arms 7, formed integrally with the pipes to furnish a stronger rest for any cooking utensil that may be placed 35 on the stove. The grate does not differ in position from any other grate in that it rests directly on the upper plate of the stove 8, and can be lifted off in the usual way when the connections 3 and 5 are disconnected. The coils thus formed are heated 40 by a flame below and likewise objects placed on the coils are heated as on an ordinary grate.

Our device has not the disadvantage of other combinations of this general character in that it is not a carrier of gas or fuel and if there is any disarrangement of the device 45 the water connections can be disconnected and the grate used, as such, undisturbed by the passage of water. If it is desired to clean the grate it can be readily disconnected in the same way and cleaned and 50 put back. The radial spider arms 7 are not absolutely necessary, but they are useful in

taking the strain off the pipes themselves. In the claims they have been referred to as spider arms but they can be of any form or number. The device is adapted for oil, gas, 55 electric or coal stoves and can be used singly or in groups and connections made accordingly.

We have found that excellent results are obtained when the cross section of the cold 60 water and the hot water outlet is smaller than the cross section of the pipes forming the spiral grate as this will provide for the expansion of the water due to heating in the grate. The coils being of spiral form 65 have a larger heating surface in a given area than the coils now in use, the coils being thus elongated to furnish a larger cubical content in a limited space.

We claim:

1. A combination water heater and grate 70 for stoves comprising an integral hollow tubular spiral grate, a cold water inlet and a hot water outlet, the grate being adapted to rest directly on the top of the stove and 75 to receive cold water from the inlet through an opening in the base of the spiral at the center thereof, the water being heated in the hollow spiral from below, and passing 80 through the outlet at the end of the spiral.

2. An integral water heater and grate for 85 stoves comprising a hollow chamber of eccentric spiral form adapted to receive cold water to be heated from below and having a series of spider arms placed across the spiral and integral with the upper walls thereof forming a rest for articles placed on the grate.

3. An integral water heater and grate for 90 stoves, comprising a hollow tubular spiral grate, provided with a series of spider arms placed across the spiral and integral therewith, a cold water inlet and a hot water outlet, the grate being adapted to rest directly on the top of the stove and to receive 95 cold water from the inlet through an opening in the base of the spiral at the center thereof, the water being heated in the hollow spiral from below, and passing through the outlet at the outer end of the spiral.

4. An integral water heater and grate for 100 stoves, comprising a hollow tubular spiral

grate, a cold water inlet of smaller cross section than the tubes of the grate, and a hot water outlet, the grate being adapted to directly rest on the top of the stove and 5 to receive cold water from the inlet through an opening in the base of the spiral thereof, the water being heated in the hollow spiral

from below, and passing through the outlet at the outer end of the spiral.

Signed at New York city in the county 10 of New York and State of New York this 3rd day of June A. D. 1920.

LOUIS G. LIPPMAN.
FREDERICK E. DIXON.
